UNITED STATES PATENT OFFICE.

WILLIAM P. HAMMOND, OF PASSAIC, NEW JERSEY.

DESIGN FOR AN ORNAMENT FOR AUTOMOBILE-RADIATOR CAPS.

52,528.

Specification for Design.

Patented Oct. 8, 1918.

Application filed April 24, 1917. Serial No. 164,294. Term of patent 3½ years.

To all whom it may concern:

Be it known that I, WILLIAM P. HAMMOND, a citizen of the United States, residing in Passaic, in the county of Passaic and State of New Jersey, have invented a new, original, and ornamental Design for Ornaments for Automobile-Radiator Caps, of which the following is a specification, reference being had to the accompanying drawing, forming part thereof.

The figure illustrates my new design.

The design comprises an ornament simulating a wheel with an applied tire upon which is mounted an eagle and a pair of flags, as shown, the flags extending from the periphery of the tire on each side of the eagle.

I claim:—

The ornamental design of an ornament for automobile radiator caps.

WILLIAM P. HAMMOND.
